RECTIFIER TUBE

Percy L. Spencer, Newton, Mass., assignor, by
mesne assignments, to Raytheon Manufacturing
Company, Newton, Mass., a corporation of
Delaware

Application July 8, 1927, Serial No. 204,320
Renewed May 9, 1930

14 Claims. (Cl. 250—27.5)

My invention relates generally to gaseous conduction apparatus and in particular to the type of device that employs a mixture of gases to facilitate starting and improve operation.

It has been found that when the source of space current carriers is derived from an easily ionizable vapor such as alkali metal vapor and a less ionizable gas, the former takes on the function of gettering or clean-up in addition to producing the low cathode drop necessary for starting and efficient operation. As a result the vaporizable substance becomes inactive in a relatively short time unless considerable quantity of the material is present. Inasmuch as the substances found most suitable for initiating discharge, e. g. caesium and rubidium, are costly and difficult to obtain, it is advantageous to relieve these metals of the gettering function, assigning the latter, wholly or in part, to a common element which will in no manner detract from the advantages offered by the more active material.

Now, I have discovered that it is practical to employ a relatively small amount of an expensive highly active alkali metal and prevent its deactivation by residual gases. In brief, this is accomplished by mixing with the caesium or other easily ionizable material, a less electro-positive and costly alkali, e. g. potassium, which readily assumes the work of clean-up without interfering with the electron liberating properties of the caesium.

The primary object of my invention is to reduce the cost of gaseous conduction apparatus. Another object is to employ minimum amount of highly active, expensive alkali metals for producing discharge. A further object is to provide in addition to the usual inert gas filling, a medium of two or more alkali vapors, one of which serves exclusively to facilitate starting and another of lower cost to remove residual gases. A still further object is to provide an efficient and convenient method of introducing and vaporizing the alkali metal mixture. Other objects and features will be apparent as the following context is perused in connection with the accompanying drawing which illustrates a preferred embodiment.

The type of discharge apparatus exemplified in the drawing is a full wave rectifier and employs an envelop 1 which may be formed of glass, hollow cathode 2 of tantalum or other refractory material, anodes 3 also of refractory material, insulating thimbles 4 preferably of lavite, and a base comprising metallic cylinder

5 secured by suitable compound to the envelop in the usual manner. The bottom of the cylinder is closed by insulating disk 6 into which the connector plugs project. The envelop 1 has re-entrant stem 7 provided with two tubular projections 8 which extend in the bottom of insulation thimbles 4, the latter being slipped over the projections and held in position by cathode 2. The anodes are mounted in openings in members 4 concentrically with projections 8 and openings 9 in the cathode, the spacing between anodes and cathode being preferably of the order of or less than the mean free path of electrons in the space. The cathode is preferably formed in two parts, the upper part taking on a partially closed shape, as conical or elliptical and the lower part 10 a cover fitting the open end of the other part. A portion of each thimble 4 is spaced from the anodes a distance of the order of or less than the mean free path of the electrons present and 20 serves to prevent the passage of current between either anode and the outer surface of the cathode. The gas employed may be any one or a combination of two or more of the monatomic group, although I prefer helium at the pressure of several millimeters of mercury.

In order to reduce the voltage loss I propose to immerse the electrodes in a highly active alkali metal vapor such as caesium and to restrain the latter from assuming the role of getter. The 30 alkali is preferably introduced by the capsule method, the vapor being liberated in a manner stated hereinafter. With the caesium in capsule 13 a quantity of another and less expensive alkali metal substance is provided, e. g. potassium, having the specific function of removing the residual gases leaving to the caesium substantially the sole function of activating the cathode. This additional alkali metal, of which potassium is but an example, is as is well known less electro-positive and of a lower atomic weight than caesium, and also has a greater affinity for impurities than has caesium.

A convenient method of combining the alkali is by mixing caesium chloride and potassium chloride and melting them together in a nickel crucible. After the fused mass is powdered up, it is placed in the capsule together with calcium chips or other reducing material in suitable form, e. g. as pill 14. I have found that one part caesium chloride to twenty parts potassium chloride functions well through I prefer to use one to ten ratio. The capsule 13, which is formed of two hemispherical portions secured together in a manner to allow gas leakage, is positioned within 55

the container by being welded to the end of a lead wire sealed in the stem and connected to a plug projecting through the base. By mounting capsule 13 in this manner, it is possible to connect a source of potential to it and other electrodes within the envelope and thus initiate a discharge therebetween.

After the tube is sealed from the pumping system and helium or other inert gas admitted, an electrical discharge is passed between electrode 10 and the juxtaposed capsule. The bombardment causes the metal of capsule 13 to glow from which heat is thermally transferred to the enclosed pill, liberating the alkali metal vapors. The latter may enter the hollow cathode through fine apertures 15 in the cover. While the action of the mixture may not be clearly understood at present, the indications point to the fact that caesium and potassium do not alloy but act as individual elements in the tube, hence the vapor pressure of one is not greatly affected by that of the other. Moreover, with the tube not operating and alkali metal condensed on the walls, the oxygenous or other deleterious gases appear to pass through the covering layer of caesium and are immediately absorbed by the potassium. In operation the caesium evidently adheres to the cathode surface, i. e. within the cathodal chamber, endowing the rectifier with properties similar to those produced by a relatively great and inexhaustible supply of pure caesium. The potassium may or may not assist in lowering the voltage drop but it unquestionably takes on the greater part, if not all, of the burden of cleaning-up the gaseous impurities.

It will be evident that the invention is not limited specifically to caesium and potassium, but embraces all instances in which one alkali metal is used for the purpose of activating a cathode surface and lowering its drop, and a second less electro-positive alkali metal usually of lower atomic weight is used to prevent said first-named alkali metal from losing its activating properties. Thus various modifications of the specific modification described above will be evident to those skilled in the art. It is accordingly desired that the appended claims be given a broad interpretation commensurate with the scope of the invention within the art.

50. I claim:

1. A gaseous discharge device comprising the combination of a plurality of electrodes, an inert gas, a mixture of caesium and potassium chlorides and a reducing agent in a metal compartment positioned in juxtaposition to one of the electrodes and means for initiating an electrical discharge between said one electrode and the compartment for heating the latter.

2. A substance for initiating discharge in a gaseous discharge device and for removing residual gases comprising a fused mass containing caesium chloride and potassium chloride and a reducing agent.

3. In an electric discharge device comprising a hermetically sealed envelope containing a cathode, an anode, the method of activating the surface of said cathode and cleaning up impurities in said device which comprises heating a mixture

of a compound of caesium, a compound of another alkali metal having a greater affinity for said impurities than caesium, and a reducing agent to a temperature at which these alkali metals are liberated within said envelope.

4. A getter for electric discharge devices comprising a mixture of a compound of caesium, a compound of another less electro-positive alkali metal, and a reducing agent.

5. A getter for an electric discharge device comprising a mixture containing one part of a compound of caesium and from ten to twenty parts of a compound of potassium together with a reducing agent.

6. The method of activating a metallic cathode for electron emission purposes and cleaning up residual gases and vapors in an electron discharge device of the caesiated cathode type, comprising heating to reaction temperatures in the device a mixture of a compound of caesium and a compound of potassium with a reducing agent to liberate these metals in the device.

7. A getter for electron discharge devices employing caesium therein, comprising a mixture of a compound of caesium and a compound of another alkali metal of lower atomic weight mixed with a reducing agent.

8. A getter for electron discharge devices employing caesium therein, comprising a mixture of a compound of caesium and a compound of potassium mixed with a reducing agent.

9. The steps in the method of producing an electrical discharge device employing a caesiated cathode which comprises introducing into the device a mixture of a reducible compound of caesium and a compound of another alkali metal of lower atomic weight with a reducing agent and heating the mixture to liberate the alkali metals in the device.

10. The steps in the method of producing an electrical discharge device employing a caesiated cathode which comprises liberating in the device from chemical compounds of which they are elements a quantity of caesium and another alkali metal which forms more stable compounds with hydrogen than does the caesium.

11. The steps in the method of producing an electrical discharge device employing a caesiated cathode which comprises liberating in the device from chemical compounds of which they are elements a quantity of caesium and potassium.

12. A getter for electrical discharge devices comprising a mixture of a compound of an alkali metal, a compound of another less electro-positive alkali metal, and a reducing agent.

13. A getter for electron discharge devices comprising a mixture of a compound of an alkali metal, and a compound of another alkali metal of lower atomic weight mixed with a reducing agent.

14. The steps in the method of producing an electrical discharge device which comprises introducing into the device a mixture of a reducible compound of an alkali metal and a compound of another alkali metal of lower atomic weight with a reducing agent, and heating the mixture to liberate the alkali metals in the device.

PERCY L. SPENCER.
